UNITED STATES PATENT OFFICE.

FREDOLF J. PETERSON, OF SALEM, OHIO, ASSIGNOR TO THE McCASKEY REGISTER COMPANY, OF ALLIANCE, OHIO, A CORPORATION OF OHIO.

CASH AND CREDIT RECORDER.

1,171,875.

Specification of Letters Patent. Patented Feb. 15, 1916.

Application filed February 14, 1911. Serial No. 608,625.

To all whom it may concern:

Be it known that I, FREDOLF J. PETERSON, a subject of the King of Sweden, residing at Salem, in the county of Columbiana and State of Ohio, have invented a new and useful Cash and Credit Recorder, of which the following is a specification.

My invention relates to improvements in cash and credit recorders for use in mercantile establishments where it is desired to extend credit, and also to keep a correct account of cash received by various clerks or those having access to the recorder. The same being true of those having access to the recorder wherein credit is extended.

The object of my invention is to construct a device of the character to which my invention pertains, that shall be simple and efficient and at the same time compact. These objects together with other objects readily apparent to those skilled in the art I attain by the construction illustrated in the accompanying drawings although my invention may be embodied in other forms as to details, the construction illustrated being chosen by way of example.

Figure 1 is a longitudinal vertical section showing the credit mechanism. Fig. 2 is a similar view showing the cash side. Fig. 3 is the top plan with the covers removed, showing the paper in proper position for use.

Similar reference numerals indicate corresponding parts in all the figures of the drawings.

The cabinet is made up of the sides 1, the ends 2 and 3 and the bottom 4, said parts being so arranged as to constitute a suitable box or cabinet in which are inclosed the various devices going to make up the operative parts together with such other parts as are necessary. Within the lower portion of the cabinet proper is located the sliding drawer 4^a. The cabinet or casing is provided with the partition 5 which partition is for the purpose of providing means for attaching the credit mechanism and the cash mechanism.

For the purpose of providing a writing table and also a rest for the cash and credit strips of paper, the table 6 is provided, which table is supported by means of suitable brackets 7 secured to the side members 1 of the cabinet proper, the table 6 being secured to the brackets and is formed of a

length sufficient to bridge the cabinet proper, thereby acting as a combined writing table and a tie-bar intermediate the sides of the cabinet proper. This is of importance, owing to the fact that the sides 60 of the cabinet should be held in proper relative relationship at all times so that there can be no springing of the sides 1, as it will be understood that if in the event the sides should be moved relatively with reference 65 to each other, the various movable parts would be liable to be thrown out of proper adjustment.

To the sides 1 of the cabinet proper are securely attached the bearing blocks 8, 70 which bearing blocks are provided with the open or semi-circular recesses 9 shown in dotted lines Fig. 1, but better illustrated in Fig. 3. These bearing blocks are for the purpose of supporting the shaft 10 upon 75 which shaft are mounted the paper spools 11 and 12, upon which spools are wound the paper strips 13 and 14. The paper strip 13 is for the purpose of recording thereon credits extended to a customer. The paper strip 14 is for the purpose of recording the amount of cash received. These paper strips are extended from the spools 11 and 12 under the tension roller 15, which tension roller is mounted upon the wire or bar 16 85 from which extend the arms 17, said arms being provided with the integral springs 18, said springs being located around the screws 19 or their equivalents, which screws are connected to the side members 1 of the 90 cabinet proper.

For the purpose of holding the springs in tension the tangs 20 are provided, which tangs are securely fixed in any convenient and well known manner to the side member 95 1 of the cabinet. The paper strips 13 and 14 extend over and rest upon the writing table 6 and from the writing table extend to the take up spools 21 and 22. The paper strip 13 extends over the top of the take up spool and the strip 14 extends down and under the take up spool 21. The paper strips 13 and 14 are unwound from the spools 11 and 12 and taken up upon the take up spools 21 and 22 by the devices 100 hereinafter described. The take up spools 21 and 22 are mounted upon the shafts 23 and 24, which shafts are held in the bearing blocks 25, which bearing blocks are connected in any convenient and well known 110

manner to the side members 1 and the partition 5 or their equivalents.

It will be understood that provision should be made for the proper removal of the spools 11 and 12 and the take up spools 21 and 22 from the cabinet proper, and in order to do this the various bearings for the shafts 10, 23 and 24 are located in open bearings. It will also be understood that provision should be made for preventing the accidental displacement of the various shafts 10, 23 and 24 and in order to provide means for temporarily holding the various shafts in proper position the latches 26 and 27 are provided, which latches are pivoted to the side members 1. The latches 26 being pivoted at one of their ends and the opposite ends provided with notches 28, which notches engage the pins 29, said notches and pins being of such relative size that the latches 26 will be frictionally held in position to hold the shaft 10. The latches 27 are preferably pivoted intermediate their ends by means of the pivot pin 30, the latches being frictionally held so that when they are brought into the position illustrated in Fig. 1 they will hold the shafts 23 and 24. It will be understood that a latch such as 27 will be provided for each separate shaft 23 and 24. Upon the shafts 23 and 24 are mounted the ratchet wheels 31 and 32, which ratchet wheels and take up spools 21 and 22 are rotatably connected together, preferably by fixedly mounting said ratchet wheels and spools upon the shafts carrying said ratchet wheels and spools; but if in the event the ratchet wheels and spools are loosely mounted upon the shafts then in that event the ratchet wheels and spools should be connected together in any convenient and well known manner. To the top or upper portion of the end member 2 are connected the angled brackets 33 and 34, which angled brackets are for the purpose of providing hinged connections for the covers 35 and 36 by means of the flanges 37 and 38, said flanges being provided with projections 39, which projections come under the upper right angled portions of the brackets 34 as best illustrated in Figs. 1 and 2.

For the purpose of normally holding the cover 35 in an elevated position, the bars 40 are provided, which bars are slidably mounted in the brackets 41 and their top or upper ends arranged to press or bear against the underside of the cover 35. For the purpose of normally holding the bars 40 in their elevated position the springs 42 are provided, which springs are located between the bottom or lower ends of the bars 40 and the top of the horizontal partition 43, which partition separates the chamber containing the paper strip actuating mechanism and the chamber in which the drawer 4^a is located.

It will be understood that the springs 42, may rest against any fixed object without departing from the nature of my invention, owing to the fact that all that is necessary is to provide some means for confining the springs so that they will hold the bars 40 in an elevated position.

Directly below the cover 35 is slidably mounted the bar 45, which bar is held by means of the brackets 46 fixed to one of the sides 1 or its equivalent. For the purpose of normally holding the bar 45 in an elevated position the spring 47 is provided, which spring may be of the form shown in Fig. 1. When the cover 35 is pressed downward so as to bring said cover substantially parallel with the top of the casing proper, the bar 40 will be moved down with said cover thereby compressing the spring 42. At the same time this downward movement of the cover 35 moves the bar 45 downward, to which bar is attached a spring detent 48, which spring detent is constructed in the same manner as the spring detent 49 best shown in Fig. 2. These spring detents are the same in both instances and their operation is substantially the same except that there is no movement of the cover 36 necessary to actuate the detent 49, said detent being actuated by the bar 50. The cover 35 is provided with the opening 51, which opening is located directly above the writing table 6. In use the cover 35 is pressed down, which downward movement moves the take up spool 21 a short distance, thereby moving the paper strip 13 by reason of the slight rotary movement imparted to the spool 21. When the cover is in its lowered position the record desired can be made upon the strip of paper 13 after which the cover 35 is permitted to assume its normal position and when again pressed down the strip of paper is again moved which presents a clean and unwritten portion of the strip of paper 13 for a new record. By pressing the cover 35 down from time to time as charges are to be made or other record placed upon the strip, said strip is intermittently unwound from one spool and taken up upon the other. It will be understood that when the cover 35 is pressed down and when in a lowered position it constitutes a convenient desk upon which the hand can be placed during the time a record is being made.

For the purpose of preventing any backward movement of the take up spools during the time the detents are moving upward and riding upon the teeth of the ratchet wheels the dogs 52 and 53 are provided which are pivoted to the sides 1 of the cabinet or otherwise connected so as to hold the same in proper position with reference to the ratchet wheels 31 and 32. To the partition 5 or its equivalent is pivotally attached the bar 54, one end of said bar being piv-

totally attached to the bar 50 and when said bar 50 is moved down the pivoted bar 54 will be rocked upon its pivotal point, which rocking movement elevates the rear end of the bar 54 and rocks the drawer catch 55 upon its pivot 56, thereby releasing the drawer catch from the drawer 4, at which time the drawer is forced outward by means of the spring 57, said spring being located between the rear end of the drawer and the end member of the casing proper. It will be understood that when the bar 50 is moved downward, the take up spool 22 will be rotated by means of the ratchet wheel and its detent, thereby intermittently winding and unwinding the paper strip 14, by which arrangement records can be made upon said strip from time to time and the strip after the record has been made taken up or wound upon the take up spool 22.

For the purpose of automatically elevating the bar 50 the spring 58 is provided, one end of said spring being connected to the partition 5 or its equivalent and the opposite end to the bar 54. For the purpose of permitting the drawer 4 to be pushed inward or in its closed position the drawer catch 55 is provided with the inclined end 59 and as the rear end of the drawer passes under the inclined end it rocks the catch 55 sufficiently to allow the rear end of the drawer to pass under and when said drawer has fully passed the inclined end 59 the spring 58 will act to lower the end of the bar 54 to which the catch 55 is pivoted, thereby lowering the catch 55 so as to bring the catch in position to engage the inner face of the rear end 60 of the drawer 4.

For the purpose of holding the sliding bar 50 in proper relative position the brackets 44 are provided which brackets are secured to the partition 5 or its equivalent. For the purpose of guiding the movement of the hinged cover 35 in its vertical movements

the flange 61 is provided, the forward end of which flange is formed of such a width that its bottom or lower edge will not pass entirely above the extreme top of the sides or partition of the cabinet or casing 1. This flange 61 as shown in Fig. 1 is provided with notches 62, which are for the purpose of providing clearance.

Having fully described my invention, what I claim as new and desire to secure by Letters Patent, is—

In a cash and credit register, the combination of a casing, a partition dividing the upper portion of said casing into two compartments, a shaft journaled in the casing, a paper carrying roll located in each of said compartments and mounted upon said shaft, a take-up spool located in each compartment and spaced from said paper carrying spools, said take-up spools rotatable independent of each other, a writing table located between said spools, a hinged cover provided with an opening above said writing table, a ratchet wheel operatively connected to each of the take-up spools, a vertical sliding bar adapted to be actuated by the cover, a spring detent carried by said sliding bar and adapted to engage with one of said ratchet wheels, a manually operated sliding bar provided with a spring detent adapted to engage with the other of said ratchet wheels, a spring actuated drawer located in said casing, a drawer catch adapted to hold said drawer in closed position and a lever connecting said door catch with said manually operated sliding bar.

In testimony that I claim the above, I have hereunto subscribed my name in the presence of two witnesses.

FREDOLF J. PETERSON.
